WEFT FEELER FOR LOOMS

Filed May 31, 1929

UNITED STATES PATENT OFFICE

CARL D. BROWN, OF HOPEDALE, MASSACHUSETTS, ASSIGNOR TO DRAPER CORPORATION, OF HOPEDALE, MASSACHUSETTS, A CORPORATION OF MAINE

WEFT FEELER FOR LOOMS

Application filed May 31, 1929. Serial No. 367,470.

The present invention relates to side slipping weft feelers for looms and is more particularly an improvement upon the weft feeler disclosed in United States Letters 5 Patent of Brown and Repass No. 1,593,426, July 20, 1926.

The object of the present improvement is to insure the clinging of the feeler to the weft until it is nearly exhausted and to prevent 10 premature side slipping especially in the event that the feeler tip encounters the tapering or conically wound portion of the weft.

The improvement is illustrated in the accompanying drawings wherein—

Fig. 1 is a plan view of so much of the feeler mechanism as is necessary for an understanding of the present invention, a portion of a bobbin and shuttle being also shown. 20 Figs. 2, 3 and 4 illustrate different modifications of the feeler tip. Fig. 5, is an enlarged cross-section on the line 5—5, in Fig. 2.

Referring to the drawings, A is the feeler stand and B the feeler shank which slides 25 back and forth and slips sidewise when needful in the manner set forth in the aforesaid Brown and Repass patent. Fig. 1 illustrates the feeler tip in contact with the tapering or conical winding C of the weft on a bobbin 30 D within a shuttle E at the detecting side of the loom.

The feeler tip of the Brown and Repass patent is provided with teeth formed by cutting and finishing the steel at the extreme 35 rear face of the tip, as illustrated at F, in Fig. 4. It sometimes occurs with this character of feeler tip, especially in the case of a closely wound smooth yarn such as rayon, that the feeler will slip sidewise prematurely. 40 In the event that the feeler tip encounters the inclined or conical portion C of the weft thus resulting in a change of bobbins with consequent waste because of the substantial amount of yarn still left on the discharged 45 bobbin. This is particularly true in case the slope of the weft encounters the rounded corner or heel G of the feeler tip instead of the teeth F.

Also, the sharp steel teeth F of the feeler 50 may bruise the yarn and, in the event that

the yarn is smooth and glossy like rayon, alter the appearance of the cloth.

The present improvement cures these defects and it consists in the new feeler tip illustrated in the drawings. As in the Brown and Repass patent the feeler shank B at its rear is bent into the form of a loop with side legs H and I and laterally extending foot or connecting bar J. In accordance with the present invention the legs and heel bar of the loop are loosely encircled by a helically coiled resilient wire K which is long enough to embrace the entire loop being maintained in position because the ends of the spring bear against the closed outer end of the loop where the legs H and I meet.

This coiled wire K constitutes the contacting tip of the feeler and its convolutions at their rear portions alone come in contact with the weft. This is equally true in the event that the feeler tip encounters the slanting surface C of the weft because the coils of the wire surround all portions of the feeler loop which are ever presented to the weft, including the rounded heel G. In other words, the coiled wire extends in a curve in excess of 70 ninety degrees forwardly beyond the reach of the slanting weft threads.

The wire coils loosely encircle the feeler loop as indicated in Fig. 5, so that each convolution of the wire is free to yield both laterally and forwardly under the impact of the weft to a sufficient extent to enable them to accommodate themselves to the yarn windings thereby engaging them adequately to 80 prevent premature slippage and to avoid bruising or damaging the yarn.

Also, it will be noted from the drawings, that every one of the convolutions of the wire embraces a portion of the feeler loop so 85 that it is internally supported and there is a definite limit to the forward yielding of all the convolutions under the impact of the weft so that each convolution is held to its work. The wire coils are supported throughout their weft contacting extent.

The wire of which the feeler tip is composed can be of varying gauge depending upon the character and fineness of the weft. Fig. 2 illustrates a coarse gauge wire and 100

Fig. 3 illustrates a fine gauge wire, while Fig. 1 illustrates a wire of intermediate gauge. This difference in gauge is indicated by the varying number of coils of the wire in each tip rather than by the diameters of the different wires which are so small as to make it difficult to show proportionate diameters while retaining the appropriate numbers of coils.

- 10 Fig. 4 illustrates the wire coil applied to a
feeler having cut teeth F. With this organization
the wire can be removed at the mill
in the event that the particular conditions
of the mill make the cut teeth preferable.
15 Also, in the event that the wire wears out
the feeler is still usable.

It is convenient to apply the wire coil to the feeler before the loop is completely closed.

I claim:

- 20 1. A side slipping weft feeler looped at its rear end and having a coiled resilient wire surrounding all portions of the loop which are presented to the weft, each convolution of the wire being capable of independently yielding sidewise and frontwardly under the impact of the weft and the forward yielding being limited by the loop.

25 2. A side slipping weft feeler looped at its rear end and having a coiled resilient wire surrounding all portions of the loop which are presented to the weft, each convolution of the wire being capable of independently yielding sidewise and frontwardly under the impact of the weft.

30 3. A side slipping weft feeler having a laterally extending foot and a forwardly extending heel in combination with a coiled resilient wire tip loosely surrounding all portions of the foot and heel which are ever presented to the weft, each convolution of the wire being capable of independently yielding sidewise and frontwardly under the impact of the weft and the forward yielding being limited by the foot and heel.

35 4. A side slipping weft feeler having a laterally extending foot and a forwardly extending heel in combination with a coiled resilient wire tip surrounding all portions of the foot and heel which are ever presented to the weft, each convolution of the wire being capable of independently yielding sidewise and frontwardly under the impact of the weft.

40 5. A side slipping weft feeler having a laterally extending foot and a forwardly extending heel in combination with a coiled resilient wire tip surrounding all portions of the foot and heel which are ever presented to the weft, each convolution of the wire being capable of independently yielding sidewise and frontwardly under the impact of the weft.

45 6. In witness whereof, I have hereunto signed my name.

CARL D. BROWN.
